UNITED STATES PATENT OFFICE

FELIX L. PIVOTO, OF BEAUMONT, TEXAS

DRILL BIT

Application filed March 13, 1931. Serial No. 522,285.

This invention relates to a novel type of drill bit.

One object of the invention is to provide a drill bit of the character described having a novel type of bit head with radial blades of novel formation arranged thereon.

Another object of the invention is to provide a bit of the character described having a head with radial blades formed integrally therewith and arranged in a novel manner on the head.

Another object of the invention is to provide a bit of the character described having a novel arrangement of discharge openings for discharging flushing fluid unto the blades.

With the above and other objects in view, the invention has particular relation to certain novel features of construction, arrangement of parts and use, an example of which is given in this specification and illustrated in the accompanying drawing, wherein:

Figure 1 shows a side view of the bit.

Figure 2 shows a vertical sectional view, 25 and

Figure 3 shows a bottom end view.

Referring now more particularly to the drawing, wherein like numerals of reference designate similar parts in each of the figures, 30 the numeral 1 designates the head which is of shell like formation and whose lower end is oval. The head has the internally threaded tapering box 2 into which the lower end of the drill stem may be screwed. This lower end usually has a drill collar having an externally threaded tapering pin to be screwed into said box. The upper end of the head is reinforced or thickened as at 3 for strength.

Leading out from the lower end of the 35 box 2 there is a water course 4 which is arranged eccentric with respect to the vertical axis of the head.

Formed integrally with the head there are the radial blades 5, 6, 7 which are preferably spaced a uniform distance apart around the head. These blades extend laterally beyond the head and project downwardly beneath the lower end of the head as shown. The lower ends of the blades are forwardly 45 curved and formed with sharp cutting edges

8, 9, 10. The lower end of each blade is provided with a vertical slot, said slots being designated by the numerals 11, 12 and 13, respectively. The blades 5, 6, 7 are progressively widened, that is, the blade 5 is 55 somewhat wider than the blade 6 and the blade 6 is somewhat wider than the blade 7 and these blades in a similar progressive manner extend out further beyond the head than the next succeeding one in front, that is, the blade 5 extends out beyond the head somewhat further than the blade 6 and the blade 6 extends out from the head further than the blade 7. The blade 5 also extends inwardly to a point near the vertical axis of 60 the head and the inner margin of the blade 6 extends inwardly, a distance somewhat less than that of the blade 5, and the inner margin of the blade 7 extends inwardly a distance somewhat less than that of the blade 6. 65 This arrangement of blades will cause the bit to progressively widen the bore as drilling progresses and the bit will leave substantially no central core of the formation. The flushing fluid discharged through the opening 4 will wash away and destroy any core 70 that may be left between the inner margins of the blades.

In front of the blades slots 11, 13, 12 are the flushing water channels 14, 15, 16 respectively, said channels being arranged progressively out further from the vertical axis of the head, that is the channel 15 is out somewhat further from said axis than the channel 14 and the channel 16 is out somewhat further from the axis than the channel 15. The water flushed through these channels will not only provide flushing fluid for the blades but will wash out the slots 11, 12, 13 and keep the same cleansed. Furthermore the flushing 80 channels 4, 14, 15, 16 leading out from the box 2 will be comparatively short and will not be liable to become blocked up with the formation but will always be open to permit the free flow of the flushing fluid.

The drawing and description disclose what is now considered to be a preferred form of the invention by way of illustration only while the broad principle of the invention will be defined by the appended claims.

What I claim is:

1. A drill bit comprising a head, a series of radial blades on the lower end of the head terminating at their lower ends in cutting edges, each blade having a vertical slot, said slots being arranged progressively out at different distances from the axis of the head, said head having channels for flushing fluid which terminate opposite said slots.
- 10 2. A drill comprising a shell-like head having an internally threaded box at its upper end, a series of radial cutting blades integral with the sides and lower end of head which extend out laterally beyond the head and are extended beneath the head, said blades each having a vertical slot in its lower end, said slots being arranged progressively outward at different distances from the axis of the head, said head having channels leading 20 downwardly from said box through the lower end of the head and terminating in front of said respective blade slots.
- 25 3. A drill comprising a shell-like head having an internally threaded box at its upper end, a series of radial cutting blades on the head which extend out laterally beyond the head and are extended beneath the head, one blade of said series being wider than the other blades, and said other blades being progressively narrowed, said blades each having a vertical slot in its lower end, said head having channels leading downwardly from said box through the lower end of the head and terminating in front of said respective blade 35 slots and said head also having a channel leading downwardly through the lower end of the head from said box and terminating eccentrically with respect to the vertical axis of the head and being located between the inner edges of the blades.

In testimony whereof I have signed my name to this specification.

FELIX L. PIVOTO.
